DESIGN FOR A CASING FOR CHAIN HOIST MECHANISM OR THE LIKE

Lurelle Van Arsdale Guild, Darien, Conn., assignor to The Kron Company, Bridgeport, Conn., a corporation of Connecticut

Application December 16, 1939, Serial No. 88,945

Term of patent 14 years

To all whom it may concern:

Be it known that I, Lurelle Van Arsdale Guild, a citizen of the United States, residing at Darien, in the county of Fairfield and State of Connecticut, have invented a new, original, and ornamental Design for a Casing for Chain Hoist Mechanism or the like, of which the following is a specification, reference being had to the accompanying drawing, forming part hereof.

Figure 1 is a face view, Figure 2 is a side view

looking from the right at Figure 1, Figure 3 is a bottom view looking from below at Figure 1, and Figure 4 is a perspective view of a casing for chain hoist mechanism or the like showing my new design.

I claim:

The ornamental design for a casing for chain hoist mechanism or the like, substantially as shown.

LURELLE V. A. GUILD.
